DRY SHAVER

Theodore Bailey, Habana, Cuba

Application February 13, 1948; Serial No. 8,218

3 Claims. (Cl. 30—43)

1

My invention relates to dry shavers, and comprises an improvement over my prior Patent No. 2,363,849, and dated November 28, 1944.

An object of my invention is to provide an improved dry shaver.

A further object is to provide an improved dry shaver which includes a plurality of cutter heads having different hair-cutting characteristics.

A further object of the invention is to provide an improved dry shaver which includes sealed-in lubricating means for certain of the working parts thereof.

A further object of the invention is to provide an improved cutter and shear bar for a dry shaver.

A further object of the invention is to provide novel means operatively connecting a motor to a reciprocating cutter for driving the latter.

A further object is to provide an improved dry shaver which includes a plurality of cutting heads, each of which includes a reciprocating cutter and novel means for reciprocating each cutter simultaneously in opposite directions.

Other objects and advantages reside in the particular structure of the invention, combination and arrangement of the several parts thereof, and/or in the particular method of operation, all of which will be readily apparent to those skilled in the art upon reference to the attached drawings, in connection with the following specification, wherein the invention is shown, described and claimed.

In the drawings:

Figure 1 is a longitudinal sectional view taken substantially on the plane of the line 1—1 of Figure 2;

Figure 2 is a longitudinal sectional view taken substantially on the plane of the line 2—2 of Figure 1;

Figure 3 is a transverse horizontal section taken substantially on the plane of the line 3—3 of Figure 2;

Figure 4 is an enlarged fragmentary longitudinal vertical sectional view taken substantially on the plane of the line 4—4 of Figure 5;

Figure 5 is a transverse vertical sectional view taken substantially on the plane of the line 5—5 of Figure 4;

Figure 6 is a view like Figure 5, but showing a modified form of cutter head;

Figure 7 is an enlarged horizontal fragmentary sectional view showing a detail of the modified form;

Figure 8 is an enlarged sectional view taken substantially on the plane of the line 8—8 of Figure 3 and showing a further detail;

2

Figure 9 is an enlarged fragmentary longitudinal vertical section through one of the cutter heads and taken substantially on the plane of the line 9—9 of Figure 1.

5 Referring specifically to the drawings, and more particularly to Figures 1 and 2, the reference character 10 designates a hollow handle or casing in which is mounted by any suitable means, not shown, any suitable motor 11 for rotating a conventional drive shaft 12. The casing, motor and shaft are conventional for dry shavers and form no part of my invention.

The drive shaft 12 has fixed thereon in 180° offset relation a pair of eccentrics 13 and 14 which operatively engage respectively the forked lower ends 17 and 18 of a pair of rock levers 15 and 16. A fixed stub shaft 19 is threadedly secured, as at 20, at one end in the handle 10 and extends inwardly thereof in parallel spaced relation to the drive shaft 12. A lubricant container 30 is concentrically disposed about said stationary shaft 19 and comprises a pair of opposed collars or sections 31 and 32 which are rotatable relative to each other. The intermediate portion of the lever 15 is journaled on the stationary shaft 19 and provides a closure for the cup-shaped section 31. The upper end of the lever 15 is forked, as at 21, for operative engagement with a reduced portion 23, Figure 2, of an actuating rod 25, a transverse arm 26 has one end fixedly secured to the other end of lever 16. A longitudinal arm or portion 27 has one end fixedly secured to the other end of arm 26, forms a closure for one end of the section 32 and terminates in a fork 22 which engages a reduced portion corresponding to the reduced portion 23 aforesaid of a drive rod 24. A lever 28 overlies the portion 27 aforesaid, and is journaled on the stationary shaft 19 and fixedly secured in any suitable manner, not shown, to the portion 27. The lever 28 includes a laterally-directed arm 28' which terminates in an upwardly-directed fork 29 which engages a reduced section corresponding to the portion 23 aforesaid of a drive rod 24'. The rods 24, 25 and 24' are on the same horizontal plane and are disposed in laterally-spaced parallel relation.

As is apparent from the foregoing, as the drive shaft 12 is rotated, the rock levers 15 and 16 are rocked in opposite directions whereby the upper fork 22 of the lever 16, together with the lever 28 and its fork 29, will be rocked in one direction, while the rock lever 15 and its fork 21 is simultaneously rocked in the opposite direction, whereby the rod 25 is reciprocated in one direction, while the rods 24 and 24' are

30

35

40

45

50

reciprocated simultaneously in the opposite direction. I have found that such opposite reciprocation of parts tends to reduce vibration.

A top of the handle 10 is provided with an end wall 33 and inset side walls 34 and 35 on which is mounted the cutter head now to be described. Referring particularly to Figure 2, it will be noted that the rods 25, 24 and 24' extend through the end wall 35 and are slidable in suitable bearings 36 formed therein. This feature is likewise well shown in Figure 3. Outwardly of the wall 35, the rods 24, 25 and 24' terminate in a sealed chamber 44 which is adapted to contain any suitable lubricant. Such outer ends of the rods are connected by upwardly-directed cross-heads 37, 38 and 39 to rods 40, 41 and 42 which extend in spaced parallel relation to the first-named rods through bearings 43 in the wall 35. The chamber 44 is closed outwardly of the wall 35 by a wall 45 on which is mounted for vertical sliding movement a closure 46 which gives access to the interior of the actual cutters. The wall 45, together with the closure 46 and the mounting means therefor, are substantially identical to the like structure shown in my prior patent aforesaid and form no part of the present invention apart from the lubricant-containing chamber 44.

The opposite inset wall 34 of the handle 10 has pivotally mounted thereon an end plate 47 by pivot means 48. A suitable screw 49 secures the plate 47 in closed position, and the plate likewise mounts a slidable closure 50 for access to the interior of the cutters. The structure of the end plate 47, pivot 48, screw 49 and closure 50 is each substantially identical to like structure disclosed in my prior patent and forms no part of this invention.

The end plates 47 and 45 are formed to provide inwardly-directed bearing-providing portions 51 on which are rotatably mounted the outwardly-flared ends 52 of a shear head 53. As a matter of fact, there are two shear heads 53, which are substantially identical and both of which are driven by the rock lever 16, as will be apparent later. Consequently, it will suffice to describe but a single one of such shear heads. In use, as the shear heads are passed over the face of the user, the heads are adapted to rotate relative to the cutters contained therein. The cutters 54 are likewise substantially identical and are tubular in form. The lower portions of the cutters 54 have fixed thereto in any suitable manner sleeves 55 which slidably receive the rods 41 and 42. Each sleeve on the end remote from the end wall 35 has secured thereto in any suitable manner a spring latch 56 which includes a depending finger 57, which seats in a notch 58 formed in the free end of each of the rods 41 and 42, Figure 8. In like manner, the rod 40 and its associated cutter and shear head, to be described later, is provided with a corresponding sleeve 55 and latch 56. As is apparent from Figure 8, with the latch in the position shown, the cutters 54 are connected to the rods 40, 41 and 42 for reciprocation therewith. At the same time, and as clearly shown in Figure 2, when the closure or end plate 47 is swung to an open position, ready access may be had to an actuating finger 59 on the free ends of the latches 56, whereby the latches may be raised to permit release of the cutters from the rods. Thus, the cutters may be slid outwardly or to the right, Figure 2, to remove them from the cutter head.

Referring particularly to Figures 2 and 9, it is

readily apparent that the cutters 54 are slotted, as at 60, to provide a plurality of cutter bars 61. The cutter bars 61, together with their slots, extend at right angles to the axis of reciprocation of the cutters 54. Moreover, as is readily apparent in Figure 9, the cutter bars 61 are triangular in cross-section with the base of the triangle providing a smooth, arcuate surface bearing against the inner surface of the shear head 53.

10 Each shear head 53 is formed to provide a plurality of diamond-shaped apertures separated by relatively narrow cutter bars 63. The long axes of the apertures 62 lie parallel to the slots 60 and the cutter bars 61 aforesaid.

15 As is readily apparent from Figure 9, with the parts arranged as last described, the cutter bars 61 of the cutters 54 force the hairs 64 against the cutter bars 63 of the shear heads with a universal shearing action. This is achieved and

20 improved upon by the fact that in normal use the shear heads are likewise rotating about the cutters, while the latter are reciprocating. Thus, the shear heads exert a shearing action of their own against the hairs 64, while the cutters are

25 likewise exerting a separate shearing action. For the purposes of providing ready cleaning of the shear heads 53, it is preferred that the corners of the apertures 62 be slightly rounded to prevent the accumulation of dirt or the like therein.

30 Such structure is clearly shown at 65 in Figure 9.

Referring now to Figures 1 and 5, and also to Figure 4, a cutter 66 is secured to the rod 40 in the manner previously described. The cutter 66 works within a stationary shear head 67 and

35 both the cutter 66 and shear head 67 are tubular in configuration and substantially quadrant-shaped in cross-section. The arcuate cutting surface of the cutter 66 is provided with a plurality of helically-disposed slots 68 which define

40 a plurality of cutter bars 69 which are rectangular in cross-section. In like manner, the arcuate face of the shear head 67 is provided with a plurality of short helical slots 70 defining cutter bars 71 and cross-bars 72. The angle of spiral

45 of the slots 70 and cutter bars 71 is oppositely disposed with respect to the like angles of the cutter bars 69 and slots 68 of the cutter. The cutter 66 and shear head 67 are particularly applicable to the cutting of relatively long hairs,

50 whereas the revolving shear heads 53 and the cutters 54 particularly adapted for regular shaving. In this connection, it should be noted, as is shown in Figure 1, that the intermediate or central shear head 53 lies in a slightly higher

55 plane than do either the shear head 67 or the outer shear head 53. This construction permits the user of the device to use either both of the shear heads 53 at once without using the shear head 67, or to use the shear head 67 with one

60 of the shear heads 53.

Referring now to Figure 6, there is shown a modified shear head and cutter corresponding to the shear head 67 and cutter 66. In this form of the invention, the shear head 167 is provided

65 with a plurality of undulated shear bars 171 connected by cross-bars 172 which extend across slots 170. As in the first-described form of the invention, the slots 170 are slightly helical in one direction. In like manner, the cutter 166 is

70 provided with a plurality of slots 164 which are helically inclined in the opposite direction and which define a plurality of cutter bars 165 which are undulated to be complementary to the shear bars 171. As in the first-described form of the invention, the cutter 166 is secured to a rod 140

75

corresponding to the rod 40 previously described and is slidably seated in a sleeve 155 and secured therein by a latch 156 which corresponds to the sleeve 55 and latch 56 of the preferred form of the invention. A suitable spring 163 is interposed between the lower part of the cutter 166 and the floor of the shear head 167. The spring 163 loads the cutting surfaces of the cutter and shear head together in a well known manner.

In like manner, a suitable leaf spring 73 is interposed between the under surface of the cutter 66 of the preferred form and its shear head 67, whereby to load the cutting surfaces of the parts into close-fitting engagement.

Referring now to Figure 7, there is there disclosed a modification of the means connecting the motor 11 to the cutters. As there disclosed, rods 125 corresponding to the rods 24, 25 and 30 of the preferred form of the invention extend through bearings 36 in the end wall 35 of the handle 10. However, inwardly of the lubricant-containing chamber 44, the rods 125 are connected to an upper rod 140 by an integral cross-head 138 rather than the separate crosshead 38 disclosed in the first-described form of the invention. Otherwise, the parts function as previously described, and it is to be understood that each of the rods 24, 25 and 30 is formed in the manner shown in Figure 7, even though but one is illustrated.

While I have shown and described what is now thought to be the preferred embodiments of my invention, it is to be understood that the same is susceptible of other forms and expression. Consequently, I do not limit myself to the precise structures shown and described hereinabove except as hereinafter claimed.

I claim:

1. In a dry shaver including a longitudinal casing adapted to serve as a handle, a plurality of spaced shear heads arranged transversely of said casing adjacent one end thereof, and a cutter mounted in each of said shear heads for reciprocatory movement with respect to said head, a drive mechanism operatively connected to said cutters for effecting the reciprocatory movement thereof, said drive mechanism comprising a transversely disposed drive shaft arranged within said casing, a pair of eccentrics arranged in face to face relation and displaced 180° with respect to each other and mounted on said drive shaft for rotation therewith, a stub shaft arranged in parallel spaced relation with respect to said first shaft within said casing and fixedly supported in said casing, a first lever arranged longitudinally of and within said casing and supported on said stub shaft intermediate its ends for rocking movement therearound, one end of said first lever being connected to one of said eccentrics and the other end being connected to the cutter of one head adjacent thereto, a first collar circumsposed about said stub shaft and having one end fixedly secured to said first lever, a second lever arranged longitudinally of and within said casing and having one end connected to the other of said eccentrics, a first arm arranged transversely of said second lever and having one end secured to the other end of said second lever, a second arm arranged longitudinally of and within said casing and having one end secured to the other end of said first arm and having the other end connected to the cutter of another head adjacent thereto, said second arm being supported on said stub shaft intermediate its ends for rocking movement therearound, a

second collar circumposed about said stub shaft and facing said first collar and having one end fixedly secured to said second arm, and embracing means on the other end of one of said collars and slidably engaging the other end of the other of said collars for securing the other ends of said collars together to thereby form a closed housing for receiving a charge of lubricant.

2. In a dry shaver including a longitudinal casing adapted to serve as a handle, a plurality of spaced shear heads arranged transversely of said casing adjacent one end thereof, and a cutter mounted in each of said shear heads for reciprocatory movement with respect to said head, a drive mechanism operatively connected to said cutters for effecting the reciprocatory movement thereof, said drive mechanism comprising a transversely disposed drive shaft arranged within said casing, a pair of eccentrics arranged in face to face relation and displace 180° with respect to each other and mounted on said drive shaft for rotation therewith, a stub shaft arranged in parallel spaced relation with respect to said first shaft within said casing and fixedly supported in said casing, a first lever arranged longitudinally of and within said casing and supported on said stub shaft intermediate its ends for rocking movement therearound, one end of said first lever being connected to one of said eccentrics and the other end being connected to the cutter of one head adjacent thereto, a first collar circumposed about said stub shaft and having one end fixedly secured to said first lever, a second lever arranged longitudinally of and within said casing and having one end connected to the other of said eccentrics, a first arm arranged transversely of said second lever and having on end secured to the other end of said second lever, a second arm arranged longitudinally of and within said casing and having one end secured to the other end of said first arm and having the other end connected to the cutter of another head adjacent thereto, said second arm being supported on said stub shaft intermediate its ends for rocking movement therearound, a second collar circumposed about said stub shaft and facing said first collar and having one end fixedly secured to said second arm, a third lever arranged longitudinally of and within said casing fixedly secured to said second arm and supported on said stub shaft intermediate its ends for rocking movement therearound, a third arm arranged transversely of said third lever and having one end fixedly secured to the adjacent end of said third lever and having the other end connected to the cutter of still another head adjacent thereto, and embracing means on the other end of one of said collars and slidably engaging the other end of the other of said collars for securing the other ends of said collars together to thereby form a closed housing for receiving a charge of lubricant.

3. In a dry shaver including a longitudinal casing adapted to serve as a handle, a plurality of spaced shear heads arranged transversely of said casing adjacent one end thereof, and a cutter mounted in each of said shear heads for reciprocatory movement with respect to said head, a drive mechanism operatively connected to said cutters for effecting the reciprocatory movement thereof, said drive mechanism comprising a transversely disposed drive shaft arranged within said casing, a pair of eccentrics arranged in face to face relation and displace 180° with respect to each other and mounted on said drive shaft for rotation therewith, a stub shaft arranged in par-

allel spaced relation with respect to said first shaft within said casing and fixedly supported in said casing, a first lever arranged longitudinally of and within said casing and supported on said stub shaft intermediate its ends for rocking movement therearound, a yoke on one end of said first lever and embracing one of said eccentrics and the other end being connected to the cutter of one head adjacent thereto, a first collar circumposed about said stub shaft and having one end fixedly secured to said first lever, a second lever arranged longitudinally of and within said casing, a second yoke on one end of said second lever and embracing the other of said eccentrics, a first arm arranged transversely of said second lever and having one end secured to the other end of said second lever, a second arm arranged longitudinally of and within said casing and having one end secured to the other end of said first arm and having the other end connected to the cutter of another head adjacent thereto, said second arm being supported on said stub shaft intermediate its ends for rocking movement therearound, a second collar circumposed about said stub shaft and facing said first collar and having 25

one end fixedly secured to said second arm, and embracing means embodying a cylindrical flange on the other end of one of said collars and slidably engaging the other end of the other of said collars for securing the other ends of said collars together to thereby form a closed housing for receiving a charge of lubricant.

THEODORE BAILEY.
